UNITED STATES PATENT OFFICE.

CLIFFORD R. SHAW, OF CHICAGO, ILLINOIS.

SOUND REPRODUCER.

1,407,002.

Specification of Letters Patent. Patented Feb. 21, 1922.

Application filed July 8, 1918. Serial No. 243,739.

To all whom it may concern:

Be it known that I, CLIFFORD R. SHAW, a citizen of the United States, and a resident of Chicago, in the county of Cook and State 5 of Illinois, have invented certain new and useful Improvements in Sound Reproducers, of which the following is a description, reference being had to the accompanying drawing, which forms a part of my specification.

10 My invention relates to sound reproducers wherein a second or auxiliary diaphragm is employed, so constructed and mounted that the tones or sounds will not only be more clearly reproduced, but the more delicate vibrations or tones, as well as the more 15 forceful or violent vibrations, will all be reproduced in a distinct, clear, manner and the original tone quality substantially maintained.

20 A further object of my invention is to provide a construction wherein the ringing sounds that are frequently encountered in phonographic reproductions will be eliminated and the hollow tone quality, of reproducers as heretofore constructed, entirely 25 obviated.

A further object of the invention is to provide a construction employing a second or auxiliary diaphragm provided with a plurality of openings for the passage of the sound waves set up by the flexible diaphragm with which the stylus-bar is connected; the openings in the second or auxiliary diaphragm being so formed and arranged that a distinct reproduction or clearer enunciation is obtainable than has heretofore been the case; the formation of the openings in the second or auxiliary diaphragm tending to increase the volume and 40 also reproducing the extremely low mellow tones which have not been obtained with phonograph reproducers as heretofore constructed.

My invention also provides a construction whereby the extraneous, mechanical sounds, namely the so-called "surface noises," will be materially diminished, with the result that the tone quality obtainable with my improved reproducer is materially enhanced and the various recorded tones or sounds reproduced with the same proportionate value which said tones or sounds possess in the original recorded selection.

The advantages of my improved construction and the functions of the respective elements will be more readily comprehended

from the following detailed description of the accompanying drawing, wherein:—

Figure 1 is a front elevation of my improved reproducer shown secured to part of 60 a tone-arm, with portions of the reproducer shell and flexible diaphragm shown broken away.

Figure 2 is a vertical sectional view, taken on the line 2—2 of Figure 1 looking in the 65 direction of the arrows.

Figure 3 is a detail perspective view of the intermediate member or auxiliary diaphragm.

Figure 4 is a front view, in perspective, 70 of the reproducer back.

Figure 5 is a perspective view of one-half of a modified form of intermediate member or auxiliary diaphragm.

In the exemplification of the invention, 75 the shell or casing of the reproducer comprises the preferably circular flanged member or ring 10 which is removably secured to the annular back 11, preferably by means of suitable screws adapted to take through 80 the screw-openings 12 shown in the back, see Figure 4. The back 11 is adapted to be properly secured to the end of the tone-arm, a portion whereof is shown at 13 in Figure 1, whereby the tone vibrations or sounds 85 may be conveyed to a suitable tone chamber in a phonograph cabinet or casing not illustrated.

The back 11 is provided with the centrally located outlet 14 and at points intermediate 90 of the outlet 14 and the periphery of the back, it is provided with a plurality of bosses 15, preferably formed integral with the back and spaced at equi-distances apart. The bosses 15 are counterbored or provided 95 with sockets adapted to receive plugs or inserts 16, preferably of resilient material such as rubber, which are adapted to protrude beyond the outer surface of the bosses so as to come into bearing relation with 100 the intermediate member or auxiliary diaphragm 17.

The auxiliary diaphragm or intermediate member 17 is provided with a plurality of openings 18, see Figure 3, circumferentially 105 arranged at a distance slightly removed from the outer periphery of the diaphragm and preferably in close relation with each other, as shown in Figure 3. The perforations 18 are arranged at a point in the intermediate member or auxiliary diaphragm 17 so as to be disposed at a point in close

proximity to the annular member or ring 10, namely at a point intermediate of the bosses 15 of the back 11 and the flanged member or ring 10, see Figures 1 and 2.

5 The auxiliary member or diaphragm 17 is held in contact with the resilient inserts or plugs 16 by a resilient washer or rubber ring 19 which in turn is maintained in contact with the member 17 by the flexible diaphragm 20 to which the stylus-bar 21 is secured at the central point 22. The diaphragm 20 in turn is held in contact with washer or ring 19, and out of contact with the inwardly disposed flange of ring 10, by 10 a resilient washer or rubber ring 23, which latter is forced or inserted beneath the flange portion of ring 10 and into contact with the periphery of the flexible diaphragm 20. As is evident from the construction 15 shown and described, the flexible diaphragm 20 is yieldingly held between the resilient washers or rubber rings 19 and 23 and permitted free vibratory movement induced by the vibratory movement of the stylus-bar 21 20 resulting from the vibratory movement encountered by the stylus or needle 24 in its travel over the indentations formed in the circular grooves of the usual phonographic record. 25

30 The intermediate or auxiliary diaphragm 17 is preferably formed of non-yielding material, preferably sheet metal and for that reason the inner circumference of the flanged member or ring 10 is preferably provided with a suitable lining of fabric, indicated at 25, in order to prevent metal to metal contact at the periphery of the auxiliary member or diaphragm 17 and therefore to eliminate any possibility of "chatter" or improper mechanical sounds. 35

40 The apertures or openings 18 in the auxiliary member or diaphragm 17 are preferably flared or enlarged toward the rear side thereof, as shown in Figure 2, thus permitting a slight gradual expansion of the vibrations or sound waves, which are set up intermediate of the flexible diaphragm 20 and the intermediate member or auxiliary diaphragm 17, in their passage rearward of 45 the auxiliary member and toward the outlet 14 in the reproducer back 11.

50 The flanged member or ring 10 is provided with the usual pair of correlated lugs 26, 26 suitably spaced apart to receive the cross-bar or head 27 of the stylus-bar. The periphery of the ring 10 at points intermediate of the lugs 26 is also provided with a pair of small tapered points 28, 28 adapted to bear against the rear side of the cross-head 27 to provide pivotal bearing therefor, 55 see Figure 1; and the cross-head is maintained in pivotal relation with the points 28 by flat springs 29, 29 which are shown removably secured to the lugs 26 by means of 60 suitably set-screws 30. The free ends of the 65

flat springs 29 are slightly bowed toward the cross-head 27 and each provided with a slightly spherical burr or point at 31, adapted to bear on the cross-head 27; the semi-spherical points or burrs 31 of the spring members 29 being preferably adapted to bear on the cross-head at points in alignment with the point of contact of the cross-head with the pointed pins or lugs 28, 28 located on the opposite side of the cross-head; thereby allowing free vibratory movement of the stylus-bar. 70

75 In Figure 5 I show a slight modification of the intermediate member or auxiliary diaphragm 17, in that the perforations thereof are beveled toward the center of the auxiliary member or diaphragm on the rear side thereof, as shown at 32. The openings are circumferentially disposed like the openings 18 in Figure 3, with the apertures, 80 however, being beveled or flared toward the center of the diaphragm, so that the sound waves may not only have slight expansion, but will also be directed in their travel toward the central outlet 14 in the reproducer 85 back. 90

95 As is evident from the construction shown and described, the bosses 15, with their resilient inserts, maintain the auxiliary member or diaphragm 17 in proper spaced relation with the back of the reproducer and the intermediate member or auxiliary diaphragm in turn places the washers or rubber rings 19 and 23 under slight compression with the result that proper spaced 100 relation between the flexible diaphragm 20 and the auxiliary diaphragm 17 is maintained; and my improved construction also tends to deaden any ringing sounds which might be produced by the sound waves 105 striking against the second or auxiliary diaphragm. 110

115 It has also been found in practice that with the bosses, whereby the intermediate or auxiliary diaphragm is supported and to that extent reduces the area or space rearward of the intermediate or auxiliary diaphragm, the slight hollowness of tone is thereby eliminated. Furthermore, placing the apertures or openings in the intermediate member or auxiliary diaphragm 17 in proximity to the outer edge of the diaphragm, each sound wave produced by the flexible diaphragm 120 will be uninterruptedly transmitted through these apertures or openings, with the result that a clearer enunciation and reproduction of the selection is obtained, than is the case where the vibrations or sound waves are transmitted directly to a single opening in the reproducer back. Furthermore, by flaring or beveling the apertures or openings in the intermediate member or auxiliary diaphragm, the volume is considerably increased 125 and extremely low mellow tones, which are usually lost with the type of reproducers 130

wherein the sound waves are transmitted from the flexible diaphragm directly through the single central opening or outlet in the reproducer back, are clearly reproduced, and 5 at the same time the surface noises resulting from the stylus traveling in the record grooves of the record are greatly reduced.

I have shown and described what I believe to be the best embodiment of my invention, but modifications may be made in 10 certain details without, however, departing from the spirit of my invention.

What I claim is:—

1. A sound reproducer, comprising a shell 15 or casing, the back whereof is provided with a central outlet and with a plurality of bosses arranged in spaced relation intermediate of said central outlet and the side wall of the shell or casing, an auxiliary diaphragm disposed on said bosses and provided with a plurality of apertures arranged circumferentially in proximity to the periphery of said diaphragm, a flexible diaphragm disposed in said shell forward of the auxiliary 20 diaphragm, and resilient means disposed intermediate of the auxiliary diaphragm and the flexible diaphragm and intermediate of the latter and the front portion of the shell

or casing whereby both diaphragms are maintained in spaced relation with each 30 other.

2. In a sound reproducer, the combination of a shell or casing having a central outlet in the rear wall thereof, the inner side of said rear wall being provided with a plurality of socketed bosses disposed intermediate of said outlet and the periphery of the rear wall and arranged in spaced relation, equi-distances apart, resilient inserts or plugs mounted in the sockets of said bosses, 35 an auxiliary diaphragm provided with a plurality of apertures arranged circumferentially in proximity to the periphery of said diaphragm, said diaphragm being adapted to rest on said resilient inserts or 40 plugs, with a flexible diaphragm arranged forward of said auxiliary diaphragm and in spaced relation therewith, and resilient means disposed adjacent the peripheries of the two diaphragms whereby the latter are 45 50 maintained in spaced relation.
